UNITED STATES PATENT OFFICE.

EDWARD E. KILBOURN, WILLIAM E. SMITH, AND ISAAC W. KILBOURN, OF NEW BRUNSWICK, NEW JERSEY, ASSIGNEES, BY MESNE ASSIGNMENTS, TO KILBOURN MANUFACTURING CORPORATION, OF NEW BRUNSWICK, NEW JERSEY, A CORPORATION OF NEW JERSEY.

HOSIERY.

1,120,506.

Specification of Letters Patent.

Patented Dec. 8, 1914.

Application filed January 25, 1912. Serial No. 673,398.

To all whom it may concern:

Be it known that we, EDWARD E. KILBOURN, WILLIAM E. SMITH, and ISAAC W. KILBOURN, citizens of the United States, 5 residing at New Brunswick, in the county of Middlesex and State of New Jersey, have invented certain new and useful Improvements in Hosiery; and we do hereby declare the following to be a full, clear, and exact 10 description of the invention, such as will enable others skilled in the art to which it appertains to make and use the same.

Our present invention relates to the class of hosiery and more particularly to the 15 manufacture of that class known as seamless hose made on circular knitting machines.

In the manufacture of stockings of this character, it is well known that the heel is made by knitting with less than the entire 20 number of needles and first narrowing and then widening the web so produced to form pockets that enlarge the web at those points for the reception of the heel of the wearer. As the heel of the stocking is subject to 25 greater strain and wear, it is customary to strengthen the web at that point by the substitution of a stronger or heavier thread or by adding a strengthening thread to the thread from which the other portions of the 30 stocking are knit.

Where the heel is knit from a heavier or stronger thread the main thread is usually withdrawn and the heavier or stronger thread is introduced at the same time at one 35 end of the series of needles knitting the heel and the change back is made at the same point. Such heels may be and often are denominated as independent heels. The threads herein referred to are clipped close to 40 the fabric in completing the stocking, and as they are not otherwise secured often leave a small hole at this point. Further than this the strain across the instep in many cases pulls upon the threads so that if there 45 be no opening it will produce a hole, or in case a hole is formed in making, the same will be increased by use to the detriment of the stocking.

When an additional thread is employed, it 50 is thrown in and out at the same point. This affects the stocking to a less degree but not unfrequently small openings are made in this construction also, owing to the strain across the instep referred to.

The object of our invention is to produce 55 a heel which shall be free from these objections and of an improved appearance.

In the accompanying drawing we have shown a portion of a stocking and have indicated thereon the nature of our invention 60 in the best form in which we have contemplated embodying it and our said invention is disclosed in the following description and claims.

In the said drawing, Figure 1 is a view of 65 our improved heel, and Fig. 2 is a greatly enlarged view of the interlocking stitches along the line of joining of the two webs knit by reciprocation of the machine. Figs. 3 and 4 are views similar to Fig. 2 showing 70 slightly modified arrangements of interlocking stitches at the joining of the two webs knit by reciprocation of the machine.

In the said drawings, A is the leg and B the foot of the stocking. When the stocking 75 is knit by beginning at the top of the leg, the same is knit in any usual manner down to the line $a-b$. As but one side of the stocking can be seen at a time the line apparently ends at the back of the stocking, 80 but it is to be understood that said line is but one-half of the real line, it extending from the point b around the back of the web to a point upon the other side of the stocking corresponding to the point b upon 85 the side in view. For convenience the line $a-b$ will be referred to as the whole line and a like plan will be pursued in respect to other lines referred to hereafter.

When the line $a-b$ is reached, a slightly 90 heavier thread is substituted or an additional or reinforcing thread is thrown in to form a "high splice" for the ankle, and if the machine before this was rotating and making circular knitting, its motion is 95 changed and reciprocating knitting is begun. The portion of the web included by the letters c, a, b, x , is then knit with the thread or threads just described on the back while on the front an equal number of 100 courses of the main thread or the thread used in the previously formed portion of the stocking, is knit, the two webs being united by the interlocking of the stitches on the line $b-x$. When the line $b-x$ is 105 reached, the needles on the front of the stocking are thrown out of operation and the heel is formed by narrowing and widen-

ing in the usual manner using a heavier thread or an additional thread as before stated, which is thrown in at a distance from the inner point of the heel.

- 5 In knitting the heel, if a heavier thread is used, it will be preferably sufficiently heavier than that used in the high splice to make the heel fabric heavier than the high spliced portion, and if the heel is knit with 10 a main and reinforcing thread, they will preferably be of such character as to accomplish the result.

When the line $d-a$ is reached the needles on the front of the stocking are thrown into 15 operation and reciprocating knitting continued with all of the needles as before the knitting of the main portion of the heel and with the thread or threads used in the part $a-b-a-c$. The stronger or heel 20 thread being thrown out and the other thrown in at a distance from the point of the heel. When the line $e-f$ is reached circular knitting may be resumed with the main thread, if desired, or the foot may be 25 knit by continuing the reciprocating knitting if preferred, continuing the same threads for the sole of the foot.

The method of uniting the two webs along the line $b-x-f$ is of great importance. 30 It is desirable that the union at such places shall be such that if a fault should occur or a stitch in the line should be broken, the stitches of such wale will not run or ravel out. If the stitches of this 35 union were to run when a break occurs the stocking would thereby be rendered practically useless. To avoid this result, I employ the form of interlocking of the threads along the line $b-x-f$ shown in Fig. 2.

40 The two webs made by reciprocating knitting are most conveniently made on a machine having two cam cylinders, each cylinder actuating the continuous series of needles of one web, a single needle at the 45 junction of each series being adapted to be actuated by both cam cylinders. When knitting the two webs the knitting cams of the two cylinders will be located at diametrically opposite points, each cam having its 50 appropriate thread guide.

The thread guide supplying one thread (indicated in the drawing by y) supplies 55 this needle with thread as it approaches the needle and also when starting on its return movement enabling it to knit two stitches at each reciprocation. Another thread guide supplies the other thread (indicated in the drawings by x) to this needle on its movement from the opposite side of the machine 60 toward the needle but does not do this as it starts on its return movement, the thread being thrown inside of the needle and not taken by it, so that of this series of interlocked stitches two are supplied by one 65 thread to one by the other, but this one

thread is interlocked with all of the selvage stitches formed from the other thread. This produces a line or wale of interlocked stitches and this wale will not run or ravel out of itself if a stitch be broken.

70 While the interlocking of the two threads for uniting the webs can be best effected by the machine construction described, we do not limit ourselves to this means. While this joining is our preferred form, we do 75 not wish to limit ourselves to this exact construction. A greater number of needles may be operated by both cam cylinders if this should be found desirable. This construction is illustrated in Fig. 3 in which 80 the thread x' is knit on two needles which also receive the other thread. Also the joining may be effected by forming a single stitch at each side as the thread and cam approach the needle but forming no stitch on 85 the return movement as before stated in reference to the thread x and shown in the drawing. This construction is illustrated in Fig. 4 in which the thread corresponding to the thread x in Fig. 2 is indicated at x^2 . 90

What we claim and desire to secure by Letters Patent is:—

1. A seamless stocking having a main leg portion and a main foot portion composed of circular knit courses, a heel pocket knit by reciprocating work and narrowing and widening, a plurality of partial courses above the heel pocket and a plurality of partial courses below the heel pocket interlocked with the corresponding courses of 95 the front portion of the stocking at each side of the stocking, the lines of said interlocked portions extending angularly from the inner point of the heel pocket and relieving the strain at the said inner point of the heel 100 pocket when the stocking is worn. 105

2. A seamless stocking having a main leg portion and a main foot portion composed of circular knit courses, and a heel composed of the usual heel pocket, a plurality of partial courses above the heel of heavier fabric than the corresponding courses of the front of the leg, and united thereto at opposite sides of the foot, by non-ravelable interlooping of the stitches of said partial 110 courses with certain stitches of said corresponding courses of the front of the leg, and a plurality of partial courses below the heel pocket proper, of heavier fabric than the corresponding courses of the top of the 115 foot, and connected therewith at each side of the foot by non-ravelable interlooping of the stitches of said partial courses, with certain stitches of said corresponding courses of the top of the foot, said interlocked portions extending in lines angularly to each other from the inner point of the heel and relieving the strain on the fabric at said point. 120 125

3. A seamless stocking having a heel com- 130

posed of the usual pocket knit of stronger material, (the thread making said pocket stronger being introduced into the web at a distance from the inner point of said pocket) and a number of partial courses above and below said pocket knit from a stronger material than the main web, the said partial courses being united with a like number of partial courses of the material of 10 the main web on the front of the stocking by an interlocking of the threads of the said partial courses on the back of the stocking with the threads of the partial courses on the front of the same.

15 4. A seamless stocking having an independent heel comprising the usual pocket knit of strong material, and a number of partial courses above and below said pocket knit of material stronger than the main web 20 but of less strength than the material of the pocket, the said partial courses united with a number of courses on the front of the stocking by an interlocking of the threads of the partial courses forming a connection 25 that will not run or of itself ravel out.

5. The herein described tubular web knit by a circular knitting machine, said web consisting of two partial webs united by a line of stitches composed of two stitches of 30 one thread alternating with one stitch of the other thread.

6. The herein described tubular web knit on a circular knitting machine, consisting of two partial webs connected by a union which 35 consists of two stitches of the thread of one web alternating with a single stitch of the thread of the other web, said single stitches being interlocked with two stitches of the other thread.

40 7. A seamless stocking having an inde-

pendent heel comprising the usual heel pocket knit of heavy fabric and a number of partial courses above and below the said pocket of heavier fabric than the corresponding courses of the front of the leg and 45 top of the foot respectively, but of less heavy fabric than the heel pocket proper, whereby the introduction of the thread forming the partial courses above the heel pocket and the termination of the thread forming the partial courses below the heel pocket will be at a distance from the inner point of the heel pocket, said partial courses being formed of 50 separate thread from the corresponding front courses and connected thereto along 55 lines at each side of the foot extending angularly to each other from the said point of the heel pocket.

8. A seamless stocking having an independent heel comprising the usual pocket knit of stronger material, and a number of partial courses above and below said pocket knit of material stronger than the main web but of less strength than the thread of the pocket, the changes from a thread of one 60 character to another having been made at a distance from the inner point of the pocket. 65

In testimony whereof we affix our signatures, in the presence of two witnesses.
